(57) CLAIM

The ornamental design for a tunic, as shown and described.

DESCRIPTION

FIG. 1 is a rear perspective view of a tunic of the present invention;

FIG. 2 is a second rear perspective view of the tunic of the present invention in an open orientation;

FIG. 3 is a front view thereof;

FIG. 4 is rear view thereof;

FIG. 5 is a first side view thereof;

FIG. 6 is a second side view thereof;

FIG. 7 is a top view thereof; and,

FIG. 8 is a bottom view thereof.

The broken lines shown in the views are included for the purpose of illustrating portions of the tunic that form no part of the claimed design.
